UNITED STATES PATENT OFFICE.

ADOLPH A. RACKOFF, OF NEW YORK, N. Y.

FOUNTAIN-BRUSH.

1,112,094.

Specification of Letters Patent. Patented Sept. 29, 1914.

Application filed November 4, 1913. Serial No. 799,191.

To all whom it may concern:

Be it known that I, ADOLPH A. RACKOFF, a citizen of the United States, residing at New York, in the county of New York and State of New York, have invented new and useful Improvements in Fountain-Brushes, of which the following is a specification.

The invention relates to brushes, and more particularly to the class of combined fountain brushes and mops.

The primary object of the invention is the provision of an article of this character wherein the brush is supplied with liquid from a reservoir on the swinging of the handle so that the liquid can be delivered to the brush, which applies it to the floor for the scrubbing or cleaning thereof, the manner of controlling the liquid being of novel form.

Another object of the invention is the provision of an article of this character wherein the mop cloth or material is mounted in a novel manner so that the floor can be scrubbed and mopped without necessitating the use of separate articles for these purposes.

A further object of the invention is the provision of an article of this character wherein the brush stock and the mop holder can be readily and easily adjusted so as to enable the article to be used for the cleaning of the floor close to the wall or in corners, the said brush stock and holder being readily detached as the occasion may require.

A still further object of the invention is the provision of an article of this character wherein the handle thereof is capable of being mounted so that the brush can be used when in standing position or for the cleaning of windows.

A still further object of the invention is the provision of an article of this character wherein the liquid is fed to the brush so that the latter may be rendered wet for the scrubbing or washing of floors, the liquid being held in a reservoir which carries both the brush and the mop holder.

A still further object of the invention is the provision of an article of this character which is simple in construction, reliable and efficient in operation, and inexpensive in manufacture.

With these and other objects in view, the invention consists in the construction, combination and arrangement of parts as will

be hereinafter fully described, illustrated in the accompanying drawings, and pointed out in the claims hereunto appended.

In the drawings:—Figure 1 is an end elevation of a combined brush and mop constructed in accordance with the invention. Fig. 2 is a rear elevation thereof, the same being partly broken away. Fig. 3 is a vertical transverse sectional view through the article. Fig. 4 is an enlarged vertical transverse sectional view through the valve. Fig. 5 is a similar view taken longitudinally through the valve. Fig. 6 is an end elevation of a modified form of combination brush and mop. Fig. 7 is a rear elevation thereof. Fig. 8 is a vertical transverse sectional view of the same. Fig. 9 is an end elevation of a further modified form of brush and mop constructed in accordance with the invention. Fig. 10 is a fragmentary vertical sectional view therethrough.

Similar reference characters indicate corresponding parts throughout the several views in the drawings.

Referring to the drawings in detail, the combination brush and mop comprises a liquid reservoir 10, formed with end flanges 11 which project beyond the side walls thereof and between which are mounted the brush stock 12 and mop 13, respectively, the flanges being formed with elongated slots 14 through which are passed winged screws 15, the latter engaged in the brush stock 12 and mop holder 13 for the fastening of the same on the reservoir.

Formed in the inner face of the brush stock 12 is a recess 16 from which lead passages 17, the same communicating with the bristles or brush body 18 mounted in the stock in any suitable manner, while formed interiorly of the reservoir 10 and integral with one side wall thereof is a stationary sleeve 19 in which is fitted a rotatable cylinder 20, the same being surrounded by means of a resilient or rubber tube 21 adapted to form a tight joint between the cylinder 20 and the sleeve 19, the sleeve 19, cylinder 20 and tube 21 being formed with apertures 22 which are adapted to be brought into registration with each other, while the reservoir 10 is formed with an opening 23 communicating with the recess 16 so that when the apertures 22 are in registration with each other the liquid within the reservoir will flow therefrom into the recess 16, thence through the passages 17 into the brush body

18 for moistening or wetting the same, the cylinder 20 being rotated for cutting off the supply of liquid from the reservoir 10 to the brush body 18 or permitting the free flow of liquid from the reservoir to the brush body in a manner presently described.

5 The cylinder 20 at one of its closed ends is formed with a central lug 24 which projects through one end of the reservoir 10 and has connected thereto an arm 25 which is adapted to ride upon a cam 26 integral with one of the legs 27 of a handle fork 28, which legs 27 carry rollers 29 which are journaled thereon in any suitable manner, 10 and are adapted to travel upon the floor, the fork 28 being provided with a detachable handle 30, and is fulcrumed on trunnions 31 projecting from opposite ends of the reservoir 10, the legs 27 of the fork 28 being formed with elongated slots 32 which receive the trunnions 31 so that the cam 26 can be shifted for depressing the lever arm 25, thereby turning the cylinder 20 in a direction for the registration of the apertures 22, 15 which are normally out of alignment with each other, so that the liquid from the reservoir 10 will be delivered to the brush body 18, the lever arm 25 being acted upon by means of a leaf spring 33 which holds it in 20 contact with the cam 26, and when pressure is released from the arm or lever 25 the cylinder will automatically turn for the shutting off of the supply of liquid from the reservoir to the brush body.

25 Trained over the mop holder 13 is a mop cloth 34, which is preferably made from felt, and the ends of which are engaged with spurs 35 suitably mounted in opposite longitudinal sides of the holder 13 for the detachable fastening of the mop cloth 34 on the holder, the said cloth being stretched taut across a cavity or hollow 36 formed in the outer face of the holder 13 so that the cloth 34 will be rendered more flexible, or allowed 30 to give when in contact with the floor.

35 Formed on one side of the reservoir 10 is a filling spout 37, provided with a removable cap 38, and through this spout the liquid is introduced into the reservoir.

40 In reversing the article so as to bring the mop into position for use, it is only necessary to tilt the handle 30 in one direction when the rollers 29 are contacting with the floor, thereby raising the reservoir 10, and 45 on the turning of the same the mop will be brought into proper working position with respect to the floor. This action is repeated when the brush is to be brought into working relation to the floor.

50 In Figs. 6, 7 and 8 there is shown a modified form of the article, wherein the reservoir 39 is provided with the end flanges 40, between which is arranged the brush stock 41 and the mop holder 42 respectively, the 55 said stock 41 being imperforate and is ad-

justably and detachably fastened to the flanges 40, and likewise the mop holder 42 is fastened to the flanges 40 in a manner as hereinbefore described. Formed in the wall adjacent to the brush stock 41 is a trough 70 43 which extends throughout the length of the reservoir, and in the outer wall of which are apertures 44 which discharge the liquid from the reservoir 39 to one side of the brush body 45, suitably mounted in the stock 41 75 for the wetting of the brush body for scrubbing purposes.

Adapted to close the apertures 44 is a shutter 46, which carries a resilient strip 47 working against the apertured wall of the 80 trough 43 so as to positively close the apertures 44 therein, the shutter 46 being supported by a hinge 48 and is acted upon by a spring 49 which is suitably supported on the reservoir 39, the spring being designed to 85 normally hold the shutter closed.

On one end of the reservoir 39 is a guide sleeve 50, in which is arranged a push pin 51, one end of which works against the shutter 46, while its opposite end works 90 against the fork 52, which is pivoted at 53 to the ends of the reservoir 39, and to which is detachably connected the ferrule 54 of a handle 55, which latter is detachable from the said ferrule 54. The ferrule 54 is 95 formed with an inverted U-shaped hook end 56 provided with a cut-away portion 57, the hook being adapted to engage the fork 52, and the cut-away portion 57 accommodates an internally threaded hollow lug 58 100 formed in the fork 52, which lug receives the reduced threaded end 59 of the handle 55 when detached from the ferrule 54, it being understood of course that when the handle is mounted as just described the 105 ferrule 54 is detached from the fork 52. It will be seen that the handle can be mounted in two positions relative to the fork 52. It will also be noted that when the fork 52 is tilted on its axis in one direction the push 110 pin 51 will open the shutter 46, thereby permitting the discharge of liquid from the reservoir 39 of the brush body 45 for the wetting of the same.

115 Mounted in the mop holder 42 at one side thereof are bearings 60 in which is journaled the pintle ends 61 of a roller 62 carrying a mopping strip 63 which is normally wound thereon, and on the unwinding of a portion of the strip the same can be trained over the mop holder 42, which is formed with a felt bed 64 against which the strip 63 lies when fastened upon the spurs 65 mounted in opposite sides of the mop holder. It will be seen that when a portion 120 of the strip becomes worn a new or unused portion of the said strip 63 can be mounted upon the mop holder for use.

125 In Figs. 9 and 10 there is shown a still further modified form of the combined 130

brush and mop, which is especially designed for use in cleaning windows or walls. The reservoir 65 of the said article has mounted on one longitudinal side thereof a tray or pan 66 into which is delivered the liquid from the reservoir 65 so that the same can be supplied to the brush body 67 therefrom, the discharge apertures 68 in the wall of the trough 69 being normally closed by the shutter hereinbefore described, and which is actuated as hereinbefore set forth.

From the foregoing it is thought that the construction and manner of operation of the device will be clearly understood, and therefore a more extended explanation has been omitted.

What is claimed is:

1. An article of the class described comprising a body forming a reservoir having 20 end flanges, a brush, means for adjustably and detachably mounting the brush between the flanges, and means for delivering liquid from the reservoir to the brush.

2. An article of the class described comprising a body forming a reservoir having 25 end flanges, a brush, means for adjustably and detachably mounting the brush between the flanges, means for delivering liquid from

the reservoir to the brush, and means for controlling said second-named means. 30

3. An article of the class described comprising a body forming a reservoir having end flanges, a brush, means for adjustably and detachably mounting the brush between the flanges, means for delivering liquid from 35 the reservoir to the brush, means for controlling said second-named means, and means for sustaining the second-named means closed.

4. An article of the class described comprising a body forming a reservoir having end flanges, a brush, means for adjustably and detachably mounting the brush between the flanges, means for delivering liquid from the reservoir to the brush, means for controlling said second-named means, means for sustaining the second-named means closed, and a handle detachably connected with said third-named means. 45

In testimony whereof I affix my signature in presence of two witnesses. 50
